UNITED STATES PATENT OFFICE.

ANTHONY J. CWIEK, OF PROVIDENCE, RHODE ISLAND.

SKIRT-MARKER.

1,119,577.

Specification of Letters Patent.

Patented Dec. 1, 1914.

Application filed March 23, 1914. Serial No. 826,741.

To all whom it may concern:

Be it known that I, ANTHONY J. CWIEK, a citizen of the United States, residing at Providence, in the county of Providence and State of Rhode Island, have invented a new and useful Improvement in Skirt-Markers, of which the following is a specification.

This invention relates to certain new and useful improvements in skirt markers, and the primary object thereof is to provide a marker which operates to mark the goods without manual interference on the part of the operator, thus leaving the hands of the latter free to manipulate the skirt.

15 A further object of the invention is to provide a device of the type set forth which can be easily and quickly adjusted so as to enable skirts which are to have varying lengths to be marked.

20 Still further, the invention aims to provide a marker which is of simple and economical construction, the parts of which are compactly assembled, and which are capable of easy operation.

25 In the drawings—Figure 1 is a perspective view of the invention, the uprights being shown only in fragment, and Fig. 2 is a vertical sectional view of Fig. 1.

The invention consists of a base 1 which 30 seats upon any suitable support and which has a pair of spaced parallel uprights 2 secured at their lower ends thereto. The uprights 2 are divided into inches and fractions thereof, as depicted in Fig. 1 of the 35 drawings.

Slidably mounted on one of the uprights 2 is a carrier 3 which is provided with a set screw 4 by means of which the carrier may be held at any position to which it is capable of adjustment along the length of the upright. The carrier 3 is provided with a pair of spaced horizontal arms 5 in which a friction wheel 6 is disposed and rotatably mounted on a pin 7 which latter is secured 40 to the arms 5. The wheel 6 has a corrugated periphery for the purpose of enabling same to easily rotate by engagement with the skirt. A carrier 8 is slidably mounted on the other upright 2 and consists of a member 9 which has a pair of spaced horizontal arms 10, which receive therebetween a tracing wheel 11, or a disk of tailor's chalk, which wheel or disk is rotatably mounted on a removable pin 12, which latter is headed 45 so as to enable the fingers to easily grip same to allow the pin to be introduced

through two registering holes 13, the holes 13 being arranged in series so as to accommodate wheels or disks of varying diameters. The member 9 is slotted at 14 to receive the 60 upright and to also receive a pair of vertical guide or clamping plates 15 which latter are provided with upper and lower flanges 16, which seat upon or engage with the upper and lower faces of the member 9, the 65 plates being thus held against movement at right angles relative to the member 9, but still allowing the member 9 to slide at right angles relative to the plates 15.

The member 9 has a wall or abutment 17 70 which engages with a coiled spring 18, the latter abutting the adjacent inner plate 15. A follower 19 is slidably mounted in the outer end of the member 9 and has a set-screw 20 engaged therewith whereby manipulation of the set screw will cause the follower to be moved inwardly or outwardly, as desired. A coiled spring 21 engages with the follower 19 and with the other of the plates 15. 80

From the above it will be apparent that the springs 18 and 21 will serve to hold the plates 15 under tension and in engagement with the opposite faces of the uprights with sufficient pressure thereagainst to sustain the 85 carrier 8 in any position to which it may be adjusted along the length of the upright. Further, by movement of the follower 19 the springs can be placed under greater or less tension so as to obtain the desired frictional engagement of the plates with the upright. The springs allow the tracing wheel or chalk disk to give when encountering seams formed in the skirt, and also serve to place the tracing wheel or chalk disk under constant pressure so as to insure effective marking on the skirt. 95

In operation, the skirt is placed between the two wheels which can be accomplished by moving the member 9 against the tension of the springs which are engaged with the relatively stationary plates 15, whereupon the hands of the operator are free to guide the skirt in straight lines or otherwise between the two wheels to attain marking thereof. 100

Having thus described my invention, I claim as new and desire to secure by Letters Patent;—

1. In a skirt marker, a base, a pair of 110 spaced uprights connected to the base, a carrier slidably mounted on one of the up-

- rights, a set screw carried by the carrier for engaging the upright, said carrier having a pair of spaced horizontal arms, a wheel rotatably mounted between the arms, and a carrier mounted on the other upright consisting of a member having a slotted part which receives the other upright, spaced horizontal arms on the member, a tracing wheel rotatably mounted between the last named arms, a pair of vertical plates which extend through the slotted part of said member and which engage opposite faces of the other upright, said plates having upper and lower flanges which slidably engage the upper and lower faces of said member, coiled springs engaged with said plates, an abutment on the member to engage one of the coiled springs, a follower slidably related to the member and engaged with the other coiled spring, and a set screw engaged with the follower and with said member.
2. In a skirt marker, a pair of uprights, a wheel carrier adjustably mounted on one of the uprights, a wheel borne by said carrier, a tracing wheel carrier having a slot which receive the other upright, a tracing wheel borne by said last named carrier, and means for mounting the second named carrier whereby the wheel thereof is held in yielding engagement with the first named wheel and the carrier is also adjustably held on the upright.
3. In a skirt marker, a pair of uprights, a wheel carrier adjustably mounted on one of the uprights, a wheel borne by said carrier, a member having a tracing wheel, said member being slotted to receive the other upright, guides engaged with opposite faces of the other upright and slidably engaged with the member, and springs borne by the member and engaged with the guides to cause the tracing wheel to yieldingly engage the first named wheel.
4. In a skirt marker, a pair of uprights, a wheel carrier adjustably mounted on one of the uprights, a wheel borne by said carrier, a member having a tracing wheel and being slotted to receive the other upright, and spring pressed means borne by said member and engaged with the upright to hold the tracing wheel of said member in yielding engagement with the first named wheel and to also hold same in adjusted position on the said other upright.
5. In a skirt marker, a pair of uprights, a wheel carrier adjustably mounted on one of the uprights, a wheel borne by said car-

rier, a member slotted to receive the other upright, to enable said member to move transversely of said other upright, a tracing wheel borne by said member, and combined spring tensioned means to hold the wheel of said member under tension in engagement with the wheel of the wheel carrier and to also hold the member in adjusted position on the other upright.

6. In a skirt marker, a pair of uprights, a carrier, a wheel borne thereby, said carrier being slotted to receive one of the uprights, a pair of vertical slidable plates extending through the slot of the carrier and engaged with opposite faces of the upright, said plates having upper and lower flanges which engage the top and bottom faces of the carrier respectively to restrict longitudinal movement of the plates relative to the carrier, a spring engaged with each plate, one of said springs being engaged with said carrier, means to engage and enable regulation of the tension of the other of said springs, and movable means on the other upright to coöperate with the wheel to enable the latter to mark the material.

7. In a skirt marker, a pair of uprights, a carrier, a wheel borne thereby, said carrier being slotted to receive one of the uprights, a pair of spring pressed elements slidably connected to the carrier and frictionally engaged with opposite faces of the upright to hold the carrier stationary in any position to which same may be moved along the length of the upright, and means on the other upright to coöperate with the wheel to enable the latter to mark the material.

8. In a skirt marker, a pair of uprights, a carrier adjustable along the length of one of the uprights, a marker carried by the carrier, means on the other upright to coöperate with the carrier to enable the marker to mark the skirt, and combined means to both resiliently support the marker, so that the latter may move toward and away from the first named means, and to hold the carrier stationary on its upright in any position on the latter to which the carrier may be adjusted.

In testimony whereof I have signed my name to this specification in the presence of two subscribing witnesses.

ANTHONY J. CWIEK.
